UNITED STATES PATENT OFFICE.

ALBERT J. BENDIX, OF NEW YORK, N. Y.

DESIGN FOR FABRIC.

SPECIFICATION forming part of Design No. 36,291, dated April 14, 1903.

Application filed March 18, 1903. Serial No. 148,450. Term of patent 7 years.

To all whom it may concern:

Be it known that I, ALBERT J. BENDIX, a citizen of the United States, residing at the city of New York, borough of Manhattan, in the county and State of New York, have invented and produced a new, original, and ornamental Design for a Fabric, of which the following is a specification, reference being had to the accompanying drawings, forming a part thereof, wherein—

Figure 1 is a face view of a piece of fabric embodying and incorporating my design, and Fig. 2 is an edge view thereof.

The leading feature of my design consists in the ornamental character of the fabric, substantially as shown in the drawings.

In the drawings, A designates a piece of fabric, and B ornamental figures arranged in horizontal rows extending across said fabric, the figures of each alternate horizontal row being arranged midway of the distance be-

tween the figures of the rows next above and below the same and producing two diagonal rows extending across the face of the fabric A.

The ornamental figures B each comprise a body portion *a*, from the upper end of which extends a stem portion *b* of a color contrasting with the body portion *a* and the entire ornamental figure B contrasting with the background formed by the fabric A, all substantially as shown.

What I claim is—

The ornamental design for a fabric, substantially as shown and described.

Signed at the city of New York, in the county and State of New York, this 16th day of March, 1903.

ALBERT J. BENDIX.
